UNITED STATES PATENT OFFICE.

DAVID F. PROVANCE, OF NEW CASTLE, PENNSYLVANIA, ASSIGNOR TO H. C. FRY GLASS COMPANY, OF ROCHESTER, PENNSYLVANIA, A CORPORATION OF PENNSYLVANIA.

DESIGN FOR A GLASS ARTICLE.

50,359.

Specification for Design.

Patented Feb. 20, 1917.

Application filed December 21, 1916. Serial No. 138,264. Term of patent 3½ years.

To all whom it may concern:

Be it known that I, DAVID F. PROVANCE, a citizen of the United States, and residing at New Castle, in the county of Lawrence and State of Pennsylvania, have invented a certain new, original, and ornamental Design for a Glass Article, of which the following is a specification, reference being had to the accompanying drawings, forming a part thereof, wherein—

Figure 1 is a side elevation of a goblet of conventional form embellished with the new design and illustrating a portion of the lat-

ter, and Fig. 2 is a similar view of the goblet illustrating the remainder of the design. The design, which consists of the configuration shown, may be formed in or on the surface of goblets, dishes, vases and other glass articles.

I claim:—

The ornamental design for a glass article, substantially as shown and described.

DAVID F. PROVANCE.
